UNITED STATES PATENT OFFICE.

LOUIS FERDINAND ALPHONSE DRUET AND GEORGES LARRABURU, OF PARIS, FRANCE;
SAID DRUET ASSIGNOR TO SAID LARRABURU.

BAKER'S OVEN.

1,119,253.

Specification of Letters Patent.

Patented Dec. 1, 1914.

Application filed March 29, 1913. Serial No. 757,618.

To all whom it may concern:

Be it known that we, LOUIS FERDINAND ALPHONSE DRUET and GEORGES LARRABURU, citizens of the French Republic, both residing at 34 Rue Vieille du Temple, Paris, in the Department of Seine, France, have invented new and useful Improvements in Bakers' Ovens, of which the following is a specification.

10 The present invention relates to certain improvements in that type of baker's oven, the floor of which, constructed as an endless band extends throughout the entire length of the oven and moves over rollers so as to carry the bread from the entrance to the exit of the oven, and returns beneath the oven to the starting point.

15 The present invention is designed to provide improvements in the method of hingeing the sole plates forming the traveling floor of the oven, and also consists in corresponding improvements in the propelling mechanism adapted to coöperate with the floor.

20 The object of these improvements is to insure that the floor travels very smoothly and regularly with a minimum of friction, and that the tension in the floor during operation of the propelling mechanism remains the same, in spite of variations in 25 temperature.

25 The floor is composed of elements of fire-resistant brick, supported by U irons shaped into connecting pieces and attached together by a hinge in order to engage with the propelling drums. One of these drums is supported by counterbalanced movable bearings for the purpose of automatically regulating the tension of the floor and permitting it to 30 expand or contract without injury.

35 The precise constructional details which form our present invention are hereinafter described with reference to the accompanying drawings, in which—

40 Figure 1 shows a longitudinal section of a baker's oven with moving floor constructed according to the present invention. Fig. 2 shows a detail view illustrating in elevation a part of the front wall of the oven and in section the mounting of the rear drum of the floor. Figs. 3 and 4 show details in longitudinal elevation and transverse section of a chain with knobs serving as the traveling chain for the floor. Fig. 5 shows a transverse section of an end of the

floor. Figs. 6 and 7 show details of the arrangement of the movable bearing with a balancing counterweight insuring the tension of the floor. Figs. 8 and 9 show the construction for the motion of a protective plate on studs with differential motion. Figs. 10, 11 and 12 show details in plan and section respectively on the lines A—B and C—D of a bar of U shape curved at its ends to hold the fire resisting bricks and forming an element of the floor.

45 The moving floor is arranged as an endless platform which travels from the front to the rear of the oven upon the drums 7, 8, supported by the respective shafts 9, 10 which turn in ball bearings 11, 12 the chains of which are fixed to the corresponding plates 1, 2. An outside mechanism comprising a wheel 13 and worm 14 insures the motion of the floor continuously or intermittently at the desired speed which is adjusted so that the duration of the passage of the bread from the entrance to the exit corresponds to the time for baking. The floor proper is formed of elements hinged together, each consisting of a support 15 of U-shaped irons in which are secured fire resisting bricks 16 formed in a rounded shape. The iron of the part 15 is correspondingly shaped except at its center for the passage 50 of the bricks to the right and left. This arrangement enables the use of very short bricks and prevents any broken bricks from falling out. The parts 15 are connected and hinged together by hinges, and they have 55 for this purpose hinged links 17 and 18 which are connected by shafts and are so shaped that the hinges serve the purpose of links of a chain and engage in the corresponding apertures arranged in the periphery of the drums 7 and 8 which act as 60 sprocket wheels.

65 In order to support the floor throughout all the part comprised between the drums, there are fixed movable chains bearing the 60 knobs 20 connected together by links 21, the whole forming an endless chain on rollers which travels freely upon an upper guide rail 22 and a lower guide rail 23. The parts 15 of the moving floor are provided at their 70 ends with pieces 24 which engage with the knobs 20 of the moving track. At each side of the moving floor is placed such a moving track to support the upper edge of the moving floor and another movable chain to sup- 75

port the lower edge. The parts 24 are shaped so as to fit below upon the knobs 20 as regards the upper floor, and in like manner the same parts 24 rest upon the knobs 20 by means of their heads when they form the lower floor. By this combination a movement of great smoothness is realized.

In order to keep the moving floor perfectly stretched between the drums in spite of the differences of length due to the dilatation, use is made of a tension device for the floor for taking it up, according to which one of the drum shafts is mounted in counterweighted bearings, so as to be movable up or down under the differing strains. Figs. 6 and 7 illustrate this arrangement. The shaft 9 of the front drum 7 is supported in bearings 11 which form slides with friction wheels 30, 31 and capable of moving on a chair or a fixed frame 32 under the influence of the traction of a balanced counterweight suspended from a chain 33 which passes over the pulley 34 and is connected at 35 to the chair or movable bearing 11. By this arrangement, when the floor expands or contracts, the counterweight compensates for the motion. The extent of these motions is of course not very great. Nevertheless, it is essential to provide a compensating mechanism which insures the constant uniform action of the drum at all times in spite of these movements; for this purpose, the worm 36 operating the worm wheel 37 mounted upon the shaft 7 extends for a sufficient length in order not to lose control of the wheel 37 in spite of the movements of the movable bearing 11.

Beneath the moving floor there are arranged one or more protective plates 40 reserved in need against the upper head of the furnace. These plates 40 are movable on rails 44 and for this purpose they are provided with casters 41. The axles 42 of

these casters are carried freely in slides 43 and this arrangement allows the movement 45 of the plates on the rails to take place with a minimum pushing or pulling effort in spite of the heat.

The floor and the roof of the baking oven are sloped from the front toward the rear 50 at an angle of 2 degrees to assist in retaining the water vapor when the oven is working. The loaves to be baked are introduced through the opening 45 and slide upon the guiding slope 46. They are thus placed 55 upon the floor which carries them from one end of the baking chamber to the other up to the discharge opening 47. The bread when properly baked is given up by the moving floor and caused to pass out by 60 means of an endless moving band 48 driven by rollers at a speed considerably greater than that of the floor of the oven.

What I claim is:—

In a baker's oven having a movable floor 65 composed of fire-resistant plates in metal frames hinged together to form an endless chain; a pair of drums one of which is operatively connected with a source of rotary motion, recesses in said drums adapted to 70 engage projections on the floor-hinges, movable chains adapted to support each side of the movable floor, rotatable wheels on said chains and fixed guide rails adapted to support said wheels, the whole so arranged 75 as to support the moving floor at its outer edges throughout its entire course.

In testimony whereof we have signed our names to the specification in the presence of two subscribed witnesses.

LOUIS FERDINAND ALPHONSE DRUET.
GEORGES LARRABURU.
